Kevin Prince**CLAIM**

We claim the ornamental design for an IV tubing organizer, as shown and described.

DESCRIPTION

FIG. 1 is a perspective view of an IV tubing organizer, showing our new design;

FIG. 2 is a front elevational view thereof;

FIG. 3 is a rear elevational view thereof;

FIG. 4 is a left-side elevational view thereof, the right-side elevational view being a mirror image thereof; and,

FIG. 5 is a top plan view thereof, the bottom plan view being a mirror image thereof.

The broken lines showing IV machines and tubes in FIG. 1 depict environmental matter and form no part of the claimed design. The remaining broken lines represent portions of the IV tubing organizer that form no part of the claimed design. The catheter is shown with a symbolic break in its length. The appearance of any portion of the article between the break lines forms no part of the claimed design.
